UNITED STATES PATENT OFFICE.

FRED W. MORGAN, OF CHICAGO, ILLINOIS.

DESIGN FOR A CEMENT-KETTLE.

SPECIFICATION forming part of Design No. 25,765, dated July 7, 1896.

Application filed November 8, 1895. Serial No. 568,362. Term of patent 14 years.

To all whom it may concern:

Be it known that I, FRED W. MORGAN, a citizen of the United States, residing at Chicago, in the county of Cook and State of Illinois, have invented and produced a new and original Design for Cement-Kettles, of which the following is a specification, reference being had to the accompanying drawings, illustrating the same.

Figure 1 represents the cement-kettle in side elevation, and Fig. 2 shows the same in top plan view.

The kettle has a flaring base portion A and a flaring upper portion B. At one side of the kettle the upper portion B has a swell b, while at the opposite side it has a similar swell b', which, however, is more elongated and may

serve as a drip-catch. The swell b terminates at the top edge b² of the upper portion of the kettle, while the drip-catch extends somewhat higher than the top edge b². This arrangement produces the form shown in Fig. 1, and also produces a top edge resembling an oval-shaped figure drawn out at its ends, as shown in Fig. 2, the whole forming a neat, symmetrical, and ornamental design.

What I claim is—

The design for a cement-kettle, substantially as shown and described.

FRED W. MORGAN.
